United States Patent Office

Des. 173,650
Patented Dec. 14, 1954

173,650

REVERSIBLE COLLAR OR SIMILAR ARTICLE

Diana Forest, New York, N. Y.

Application February 26, 1954, Serial No. 29,236

Term of patent 3½ years

(Cl. D3—8)

Fig. 1

To all whom it may concern:

Be it known that I, Diana Forest, a citizen of the United States of America, residing in city of New York, county of New York, and State of New York have invented a new, original, and ornamental Design for a Reversible Collar or Similar Article, of which the following is a specification, reference being had to the accompanying drawing, forming part thereof.

Fig. 1 is a plan view of a reversible collar or similar article, showing my new design.

Fig. 2 is a perspective thereof as it appears in fastened and reversed position.

I claim:

The ornamental design for a reversible collar or similar article, substantially as shown and described.
